CLAIM

The ornamental design for a board for tracking the status of firefighting equipment, as shown and described.

DESCRIPTION

FIG. 1 is a top and front perspective view of a board for tracking the status of firefighting equipment showing my new design;

FIG. 2 is a top plan view thereof, the bottom being a mirror image of that shown;

FIG. 3 is a left side elevational view thereof, the right side being a mirror image of that shown;

FIG. 4 is a top and front perspective view of an alternate embodiment thereof, the broken-line disclosure of a tag being for illustrative purposes only and forming no part of the claimed design;

FIG. 5 is a right side elevational view of the embodiment of FIG. 4, the left side being a mirror image of that shown; and,

FIG. 6 is a top plan view of the embodiment of FIG. 4, the bottom being a mirror image of that shown.
